GLENN D. ANGLE, OF CINCINNATI, OHIO, ASSIGNOR TO THE LE BLOND AIRCRAFT ENGINE CORPORATION, OF CINCINNATI, OHIO, A CORPORATION OF OHIO

VALVE-MECHANISM HOUSING

Application filed October 23, 1928. Serial No. 314,471.

My invention relates to radial engines, and more particularly to the valve operating mechanisms thereof.

In engines of the radial air-cooled type 5 that are so generally used for aircraft, the valves are operated as a rule by push rods and rockers from a cam or cam ring whose axis is concentric with the crankshaft. It frequently happens that considerable angularity exists between the push rod and either 10 the cam follower, which is supported or guided in some section of the crankcase, or the valve rocker arm. Should this angularity be excessive and the loads high, the result is 15 side thrust loads that develop rapid wear on the valve gear mechanism. It is therefore desirable to so arrange the design that the angularity is at the minimum possible.

Since the valves are usually placed at an 20 angle to the cylinder axis which cannot parallel the axis of the cam follower, or the rockers be conveniently made long enough so that the ends receiving the push rods are in the plane of the cam followers, it is practically 25 impossible to eliminate the undesirable angularity entirely. However, in the arrangement herein proposed an approach to an ideal condition is obtained.

In this design the cam follower axis falls 30 at some convenient angle to the axis of the cylinder with which it is associated and the valves are inclined in the cylinder head at the angle considered best for good operating conditions. It is proposed to rotate the plane 35 of the rocker arm about the axis of the valve until the end of the rocker is substantially in line with the axis of the cam follower.

In order to accomplish this proposed mode 40 of alignment thus avoiding difficulties inherent in prior constructions, I have devised a certain novel arrangement and structure which permits of the arrangement noted, and provides many advantages over any enclosed valve gear of which I have knowledge.

45 I accomplish my objects by that certain construction and arrangement of parts of which a typical illustration is made in the drawings and described in the specification that follows, the novelty inherent therein 50 being set forth in the appended claims.

In the drawings:—

Figure 1 is a top plan view of one of the cylinders of a radial engine, showing one of the rocker arm housings in place and another removed.

55 Figure 2 is a detail showing a cylinder in phantom, with the valves and valve operating structure in section.

Figure 3 is an elevation of a cylinder with 60 one of the valve arrangements in section at a different view point from that shown in Figure 2.

Figure 4 is an enlarged section of a rocker arm housing, showing a rocker arm, as supported therein in plan view.

65 Figure 5 is a view of the same parts as shown in Figure 4, with the rocker arm in elevation and the housing in vertical section.

I have illustrated in the several views an 70 air-cooled internal combustion engine cylinder 1, which is one of the cylinder elements of a radial engine. Located in the head of the cylinder are the usual valve seats 2 and 3 for inlet and exhaust. The valves 4 have stems 5 guided in the bosses formed in the cylinder head above the seats, said stems being located so that their ends are engaged 75 by rollers 6 on the rocker arms, whereby the valves are depressed.

It will be noted that the valve seats are 80 at an angle, as are the guides and valve stems. The angle in my new improvement may be varied to suit the requirements of best operation of the engine without much regard to the push rod and rocker arm construction.

85 Around the opening in the cylinder beyond each valve chamber I form a symmetrical flange 7 which can have the same angle as the valve seat. I have shown a circular 90 flange, but some other symmetrical shape will serve.

The rocker arm housings 8 may be uniform 95 for all exhaust and intake valve assemblies, and will have a flange 9 to match the symmetrical flange around the valve chambers in the engine cylinders.

In building the engine, the position of the rocker arm housings is determined in such a way as to place the rocker arms in a plane 100

passing through the axis of the push rod device.

First describing a typical push rod device, I have shown the valve operating cam or cam ring 10 upon which the rods 11 are arranged to rest, usually some type of antifriction roller being used to engage the cam. The rods are supported in bosses in the crank case, beyond the position of the cylinders thereon, 10 and project at whatever angle is convenient, outwardly to the rocker arms.

The rocker arms 12 are mounted in suitable bearings 13 in the housings 8, and have bifurcated ends, in the instance shown, to engage the stems of the valves. The rear ends of the rocker arms in the illustrated instance are split and formed into a boss 14, which is arranged to engage a socket piece 15 clamped in the boss by drawing the ends 20 of the split portion thereof together with a bolt, as indicated. The socket pieces may also be threaded, although this part of the arrangement is not required, any rocker arm structure and means of engagement by the 25 push rods being satisfactory. Springs 16 about the valve stems keep the valves closed unless operated by the push rods and in the instance shown, apply spring pressure to the push rods to keep them against the cam.

30 The push rod ends are seated in the sockets held in the rocker arms, the housings having suitable apertures to receive the rods. I have illustrated the housings as entirely enclosing the rocker arms except for this orifice, which 35 may be protected as desired.

In setting the housings in place, it is apparent that the flanges on the housings will engage fully in any position revolved about on the flanges around the valve chamber 40 openings.

All housings will have a series of holes formed about the flanges thereof, as indicated at 17 in the enlarged view Figure 4. The flanges on the cylinder heads will have holes 45 tapped and threaded therein, which will permit the housings to be swung to an angle with relation to the cylinder, which will bring the rocker arms within the housings into coincidence with the planes passing through the 50 push rods for the housings in question.

Thus I have shown the flange 7 in Figure 1 without any holes indicating its condition before the location of the rocker arm housings has been determined.

55 All rocker arm housings can be manufactured alike for intake and exhaust, the angle of the valves can be arranged to suit the engine design without regard to the push rods, the push rods can be extended radially 60 at any convenient angle to the axis of the crank shaft journals, and the shifting of position of the rocker arm housings at will, will prevent the development of twisting strains, due to improper angularity of the push rods 65 with relation to the rocker arms.

Having thus described a typical instance of my invention, what I claim as new and desire to secure by Letters Patent, is:—

1. In combination in an engine cylinder having a valve and valve stem therein, a flange formed about an opening in said cylinder through which the stem of the valve projects, said flange being concentric with the valve stem axis, and a housing with a rocker arm therein for engaging the valve stem, said housing having a flange of a shape to take a full seat in various positions of radial adjustment upon the said engine flange, for the purpose described. 75

2. In combination in a cylinder for engines having a valve mounting structure, a valve therein, and an exposed stem for the valve, a circular flange on the cylinder about the said exposed stem and concentric therewith, and a housing containing a rocker arm which is mountable upon said flange in a variety of 85 radially adjusted positions.

3. In combination a cylinder in a radial engine having a valve seat and valve at any desired angle, a cam and push rod device for operating said valve, said valve having a stem, a rocker arm having connection with the push rod, and with the valve stem, said rocker arm having a housing in which it is mounted, and said housing mounted on the engine at 90 an angle which will bring the rocker arm into the same plane as the axis of the push rod. 95

4. In combination a cylinder in a radial engine having a valve seat and valve at any desired angle, a cam and push rod device for 100 operating said valve, said valve having a stem, a rocker arm having connection with the push rod, and with the valve stem, said rocker arm having a housing in which it is mounted, and means for mounting said housing on the cylinder 105 so that the rocker arm therein will lie in the same plane as the axis of the push rod.

5. A cylinder for a radial engine having a flange about the valve operating chamber thereof, said flange concentric with the valve, 110 a rocker arm housing, and means for mounting said housing in a variety of radial positions upon said concentric flange.

GLENN D. ANGLE.
